UNITED STATES PATENT OFFICE

2,519,535

CONTROL CIRCUIT FOR HIGH SURGE CURRENTS

Clarence E. Atwood, Mount Prospect, Ill., assignor,
by mesne assignments, to Huber Manufacturing Co., Chicago, Ill., a corporation of Illinois

Application August 13, 1948, Serial No. 44,127

11 Claims. (Cl. 315—240)

1

This invention relates to the control of gaseous discharge tubes. More particularly it has reference to a glow discharge tube of the type used for photoflash photography wherein the tube provides an intense white flash of short duration and in substitution of the conventional explosive flash bulbs in common use.

Such glow discharge tubes are a well-recognized article of commerce. For example, one type sold by General Electric Company under the designation FT-214 employing xenon as the gaseous agent has a working voltage of 2000 and yields a practically pure white light of high intensity and of approximately $1/1000$ second duration when subjected to the discharge of a condenser of approximately 125 microfarads. Various circuits for applying the charge of the condenser to the lamp have been evolved, but in all of these prior arrangements known to me, the circuit has been closed by means of a relay actuated by a push button or equivalent device under the control of the operator. The high voltage at the instant the contacts begin to close is sufficient to form an arc therebetween, and the relatively heavy current then flowing combined with the blow of contact frequently welds the relay contacts together.

I have found that it is unnecessary to close the relay contacts completely since the glow discharge occurs even before the contacts are actually closed, and that ionization voltage may be impressed on the tube without a solid conducting path. I attain this object by an arrangement which will permit the contacts to approach but not touch physically, and rely upon the arc thus initiated across the contacts to form a current-conducting path.

Accordingly the principal object of my invention is the provision of a system for actuating a glow discharge tube which does not utilize physically contacting members for completing the circuit to the tube.

Another object is to provide a system as aforesaid in which the circuit closing members are included in a relay.

A further object is to provide in the relay as aforesaid means for adjusting the contacts in accordance with the operating characteristics of the tube.

An additional object contemplates a system in-

2

cluding a relay as aforesaid and a network in shunt with the tube for facilitating ionization thereof.

Generally speaking the invention consists in providing a system including a relay having a pair of hemispherical contacts and means effective upon energization of the relay for permitting the contacts to approach each other a predetermined amount, but not to touch, in order to effect a condensive action within the contacts proper and so to control the potential available from the main charging condenser and the effect thereof in initiating and maintaining glow discharge in the flash lamp.

In the drawing which shows several modes in which the invention may be embodied in practice:

Fig. 1 is a circuit diagram of a preferred form of the invention; and
Figs. 2, 3 and 4 are circuit diagrams of alternative embodiments thereof.

In all of the figures the means for charging the main condenser and for completing the circuit through the relay operating coil have been omitted as capable of wide variation depending upon the designer and the purpose, and as forming no part of the invention per se. In each of the figures the reference letters S—S will identify the leads going to a source for impressing a charge on the main condenser 10, and the letters A—A the leads connecting the relay coil 11 to a suitable circuit for energizing the same.

Turning first to Fig. 1 there is shown a glow lamp 12 of the photoflash type, for example, a glass envelope serving as protector for a tubular glass helix containing xenon or other suitable ionizable gas yielding the desired spectrum when subjected to a predetermined voltage, the leads 13 and 14 being connected to the anode and cathode respectively of the helix as is understood in the art.

Condenser 10 may be of any suitable capacity, say 125 microfarads, and is charged to a potential of approximately 2000 volts by connecting the same for a sufficient period of time to a charging source as heretofore pointed out. Relay 17 is provided with the armature 18 bearing a substantially hemispherical contact 19 adapted to cooperate with a similar fixed contact 21. These latter are preferably of silver for good conductivity.

Armature 18 is provided with a motion-limiting screw 22 and locknut 23, the tip of the screw being adapted to abut some fixed part of the relay, here shown for convenience as the core 24. Armature 18 is shown in its back position and the amount of movement thereof to front position is indicated by dimension *a*, this being variable by means of the screw 22 and nut 23. However, the gap *b* between the contacts 19 and 21 is greater than *a* by a predetermined amount predicated upon the parameters of the system.

Operation of the system just described is as follows. Assuming condenser 10 has been fully charged and that the relay 17 is deenergized, a potential exists across the condenser 10, and by leakage, across the contacts 19 and 21 and the elements of the lamp 13. At this time the potential across 19 and 21 is insufficient to cause current to flow across the gap *b* and similarly the voltage across the elements of the lamp 13 is inadequate to trigger the same. However upon closure of the circuit through coil 11 the armature 18 is actuated to bring contacts 19 and 21 closely adjacent, i. e. defining a gap *b* minus *a*. The electrostatic capacity of the condenser formed between 19 and 21 as electrodes, and the air gap therebetween as the dielectric, changes rapidly as the relay operates, resulting in a sudden decrease of potential across the gap and a sudden increase of potential across the lamp 12. By initially establishing across condenser 10 a potential which is well above the ionization potential of the lamp, the sudden application of additional potential due to closing movement of the contacts 19 and 21 is sufficient to start ionization of the lamp. With the lamp in an ionized state, and therefore conducting, substantially the entire potential of the capacitor 10 is imposed upon the gap *b* minus *a* causing an arc discharge thereacross which effectively closes the circuit including the condenser 10 and the lamp 12 for ignition of the lamp.

It will have been concluded from the foregoing that the objectionable welding of the relay contacts inherent in prior systems has been avoided by my invention, and with no loss of efficiency, since the whole charge of the condenser 10 is effective in actuating the lamp 12. Moreover, in such prior devices the heat generated at the relay contacts was accompanied by the force of closing resulting in a forging action which intensified the sticking due to the welding action alone.

In the invention system contacts 19 and 21 are hemispherical to provide a concentrated electrostatically stressed region therebetween, and are preferably large as compared to similar contacts in prior relays to provide wider distribution of the arc and hence less pitting of the contact surfaces. By employing silver the conducting oxides thereof formed by the arc do not result in any diminution of the effective arcing area. Moreover, the low melting point of silver and its consequent vaporization under the heat of the arc contributes appreciably to conductivity across the gap *b* minus *a* by migration of silver ions.

In Fig. 2 is shown an alternative arrangement like that of Fig. 1 except that a resistor 26 of relatively high value, as on the order of 2 megohms, has been shunted across the conductors 13 and 14. Thus an additional leakage path is provided to augment the accrual of potential across the contacts 19 and 21. This form of the invention system provides more positive action when the leakage current is low or when the difference

between the ionization voltage of the lamp and its glow discharge voltage is of low order.

Fig. 3 shows still another form similar to that of Fig. 2 except that a capacitor 27 replaces the resistor 26. The capacitor is preferably of small capacity, say 0.0005 microfarad and necessarily of high voltage. Capacitor 27 serves to transfer a charge from condenser 10 to the contacts 19 and 21.

The modification of Fig. 4 is similar to that of Fig. 1 except for the addition of a second armature 29 including contact 31, and a fixed contact 32. Moreover a capacitor 33 of the same order as that of Fig. 3 is bridged across armatures 18 and 29. Contacts 31 and 32 are adapted to close before contacts 19 and 21 approach arcing distance and thus to shunt capacitor 33 across the latter. Thus a small initial charge is transferred to the lamp 12 sufficient to initiate ionization.

It will be understood that in general any suitable network may be shunted across the lamp, the resistor 26 or condenser 27 being only typical arrangements. The characteristics of the network generally are such as to facilitate ionization of the tube when used in conjunction with the invention system.

While I have shown particular embodiments of my invention, it will be understood, of course, that I do not wish to be limited thereto since many modifications may be made, and I therefore contemplate by the appended claims to cover any such modifications as fall within the true spirit and scope of my invention.

Having thus described my invention, what I claim and desire to secure by Letters Patent is:

1. A system for controlling the ignition of a glow discharge tube comprising a capacitor for storing a charge capable of causing the discharge, circuit means connecting said capacitor and the tube, said circuit including a pair of juxtaposed electrodes in electrically condensive relation, means supporting said electrodes for movement from a predetermined spaced relation to a more closely spaced relation, and a device for moving said electrodes from one said relation to the other for varying the capacity between said electrodes.

2. A system as in claim 1 in which said electrodes are substantially hemispherical and positioned with their convex faces opposed.

3. A system as in claim 1 in which said device includes means for adjusting the minimum spacing between said electrodes.

4. A system as in claim 1 in which said device is a relay including a movable armature, said armature supporting one of said electrodes and the other electrode being stationary.

5. A system for controlling the ignition of a glow discharge tube comprising a capacitor for storing a charge capable of causing the discharge, and a pair of electrodes providing a second capacitor, said two capacitors being connected in series circuit relation with the tube, and means for varying the spacing of said electrodes from a finite spacing to zero for transferring a part of the charge to the tube by electrostatic coupling, and for transferring substantially the balance of said charge to the tube by conduction.

6. A system as in claim 5 in which said spacing varying means includes a relay means for actuating at least one of said electrodes.

7. A system as in claim 6 in which said relay is provided with an armature for supporting one of said electrodes and the other said electrode being fixed.

8. A system as in claim 5 in which said spacing varying means comprises a relay having one armature for supporting one of said electrodes, the other said electrode being fixed, and a second armature and fixed contact cooperative therewith, a condenser connected across said armatures, and said fixed contacts being connected together.

9. A system as in claim 5 characterized by a resistor in shunt with the tube.

10. A system as in claim 5 characterized by a 10 third capacitor in shunt with the tube.

11. A system as in claim 5 characterized by an impedance network in shunt with the tube.
